UNITED STATES PATENT OFFICE.

SAMUEL MCMILLEN, OF MINNEAPOLIS, MINNESOTA.

LEDGER-INDEX.

SPECIFICATION forming part of Letters Patent No. 695,226, dated March 11, 1902.

Application filed May 21, 1901. Serial No. 61,234. (No model.)

To all whom it may concern:

Be it known that I, SAMUEL MCMILLEN, of Minneapolis, county of Hennepin, State of Minnesota, have invented a certain new and 5 Improved Ledger-Index, of which the following is a specification.

The invention relates to an improved system of indexing for ledgers.

In a ledger-index as usually made the names 10 are placed in regular vertical columns under the second or third letter of the name, the initial letter being on the tab. In large sets of books there are frequently several 15 pages of names, and as many of them have the same second or third letter it often happens that the bookkeeper is compelled to look through a column running over several pages to find the name under which a certain account is indexed.

20 The object of the invention is to provide a system of indexing under which the names will be irregularly arranged and the bookkeeper will be able to quickly locate any name on an index-page, and hence be able to 25 readily turn to any account.

The invention consists generally in a page having a tab bearing the initial letter, said page being provided with a series of vertical columns and a horizontal row of letters arranged 30 in groups in said columns at the top of the page, said groups representing combinations of two or more successive letters following the tab letter or letters of a name under which an account is indexed.

35 Further, the invention consists in various constructions and combinations, all as hereinafter described, and particularly pointed out in the claims.

In the accompanying drawings, forming 40 part of this specification, Figure 1 is a plan view of a ledger-index page, illustrating my invention. Fig. 2 is a similar view of another page of the index.

In the drawings, 2 represents the index-page having at its inner edge a flexible binding-strip 3, provided with eyelets 4, permitting the leaf to be loosely bound in book form. On the opposite edge of the leaf near the top thereof is the usual tab 5, upon which the 45 initial letter of a name is placed. I also prefer to place in smaller type on said tab the letter following the initial letter of the name.

On this tab I have shown two letters "I" and "O," the leaf to which the tab is attached being appropriated for names whose second letters correspond thereto. Each page of the leaf is divided by horizontal lines 6 into a series of rows 7, wherein the names are written, and these lines are crossed at right angles by substantially vertical lines 8, forming 6c vertical columns 9. In the squares or spaces formed by the intersection of the lines 7 and 8 I provide combinations of letters corresponding to two or more successive letters following the initial letter of the tab. These combinations are such as are usually found in the names of individuals, firms, or business 65 houses with which it may be necessary in the course of business to open a ledger account. For instance, at the left-hand side of the page 70 I have provided combinations—such as "ib," "id," "ie," "ig," &c.—being the second and third letters of the several names, the first or initial letter being represented by the one on the tab. 75

In Fig. 1, as heretofore stated, I have shown a page appropriated for names having "I" and "O" for the second letter. Hence I have divided the page, appropriating the right hand for the names whose letter is "O." As will 80 be noted by an examination of the figure, the names are, owing to the manner of indexing, irregularly arranged on the page, so that a bookkeeper wishing to look up an account can readily locate the name in the index, al- 85 though there may be several pages under the tab-letter. For instance, should he desire to look up the account of the Livingstone Advertising Company he will turn to the page whose tab bears the letter "L," and then, be- 90 ginning at the top of the columns containing the letters "IV" corresponding with the sec- 95 ond and third letters of the name he is looking for, will follow down said column and be able almost immediately to locate the name on the page. Having found the page, it is of course a simple matter to determine the page of the ledger where the account is to be found. The second letters of the name, which I prefer to place on the tab with the initial letter, 100 will correspond in all cases to the first letter of the combinations at the top of the page, and these second letters will indicate that the names whose second letters correspond to the

alphabet letters between the letters on the tab will also be found on the tab-page or those following it.

In Fig. 2 I have shown the "M" tab-page 5 having the second letter "a," the page being entirely appropriated for names whose second letter is "a." In indexing a ledger many names will be found beginning with "Sch," and these letters will be placed on the tab, 10 while the combinations of the fourth and fifth letters of the names will be placed in the vertical columns. It will also be found in indexing that many names begin with "St," in which case I prefer to make combinations of 15 the second and third letters of the names. I am not, therefore, confined in my combinations to the second and third letters of the names, as it will be found convenient to index a great many names under the third and 20 fourth or the fourth and fifth letters. As the pages will be ruled in exactly the same way and the combinations arranged in a corresponding manner to those which I have shown in the drawings, I have not thought it necessary 25 to illustrate pages showing combinations of the third and fourth or fourth and fifth letters.

I have shown the invention applied to the 30 pages of what is known as a "loose-leaf" ledger-index; but obviously the same system of indexing may be used in connection with a bound index.

As shown in Fig. 2, I prefer to appropriate 35 several leaves for names such as those beginning with "M" and provide tabs thereon bearing the index-letter and one or more vowels, as "Me," "Mi-o," and so on through the vowels, the number of pages used depending upon the probable combinations required 40 to index the names whose initial letter corresponds with the primary letter on the tab. Where the invention is employed in connection with a loose-leaf index, the bookkeeper may insert new pages as the others become 45 filled and remove any of the pages whereon

accounts are indexed that have been closed or balanced.

The principal advantage of my improved system of indexing lies in the fact that the bookkeeper, having the initial or index letter 50 and the second letter of a name before him on the tab, can open the index to any group of leaves where the name will be found under which the desired account is indexed. Then finding the combination of letters corresponding 55 to those of the name sought he can follow down the column, although it may extend several pages, and very quickly locate the name.

Having thus described my invention, I claim as new and desire to secure by Letters 60 Patent—

1. A ledger-index, consisting of a page having a tab bearing the initial letter of the names, said page being provided with a series of vertical columns and a horizontal row of letters 65 arranged in groups in said columns at the top of the page, each of said groups representing a combination of two or more successive letters following the tab letter or letters of the name under which an account is indexed. 70

2. A ledger-index consisting of a page having a tab bearing a letter which corresponds to the initial letter of the names placed on the page, a series of vertical columns provided on said page, and a horizontal row of letters arranged 75 in groups in said columns, there being but one group in each column, said groups representing combinations of the second and third letters of the name under which an account is indexed, whereby the names when 80 written on the page under the combinations corresponding respectively to their second and third letters will be irregularly arranged, for the purpose specified.

In witness whereof I have hereunto set my 85 hand this 17th day of May, 1901.

SAMUEL McMILLEN.

In presence of—

RICHARD PAUL,
M. C. NOONAN.
